INCINERATOR

Mick A. Naulin, Milwaukee, Wis.

Application July 25, 1955, Serial No. 524,223

6 Claims. (Cl. 110—8)

This invention relates to incinerators and refers more particularly to improvements in incinerators of the type shown in the copending application of Abner M. Naulin (now by change of name Mick A. Naulin), Serial No. 394,608, filed November 27, 1953, now Patent No. 2,805,633, of which this is a continuation in part.

That application discloses an incinerator having front, rear, top and side walls of modular construction, and having a partition wall extending from one side wall to the other, intermediate the front and rear walls, to separate the interior of the incinerator into a combustion compartment in front of the partition wall and an expansion chamber behind the partition wall. The top edge of the partition wall is spaced below the top wall to permit combustion gas from the combustion chamber to flow thereover into the expansion chamber, whence combustion gas leaves the incinerator through an outlet centered in the rear of the incinerator, near the top thereof.

Behind the partition wall is a drop wall which extends from one side wall to the other and which depends from the top wall, with its lower edge spaced below the upper edge of the partition wall to cooperate therewith in defining a narrow throat through which the combustion gas flows before entering the expansion chamber. As the gases flow through this throat they induce secondary combustion air through inlets in the side walls of the incinerator, and in the expansion chamber this induced air is utilized for secondary combustion of uncombusted vapors and particles carried in the gas stream. The encouragement of this secondary combustion in the expansion chamber is essential to the minimization of odor, which is caused for the most part by the emission from the incinerator of uncombusted or incompletely combusted gases and microscopic particles. In the expansion chamber, too, the combustion gas stream should somehow be caused to drop any fly ash or dust particles which it may be carrying with it.

In some instances the expansion chamber has heretofore been formed as a tortuous passage defined by a plurality of baffles, but this type of expansion chamber had the disadvantage of promoting and maintaining a relatively high velocity flow of the combustion gases throughout their entire passage through the expansion chamber. This followed from the fact that the passage defined by the baffles was comparatively narrow for its entire length. The gas stream thus necessarily flowed therethrough at high velocity carrying with it to the stack all of the fly ash and dust particles from the combustion chamber.

In other incinerators, including that of the aforesaid copending application, the expansion chamber provides a relatively large unobstructed space in which the gases may be substantially decelerated in their flow from the combustion chamber to the smoke outlet and in which they

2

may therefore drop most of the entrained dust and fly ash. However, this latter expedient, while satisfactory in some cases, has not always proven to be fully effective, although the incinerator of said copending application is 5 greatly superior to most previous incinerators with respect to its output of fly ash, dust, visible smoke and odor.

It has now been learned that incinerators of the type having an unobstructed expansion chamber have heretofore been unsatisfactory because combustion gases leaving the throat conjointly defined by the partition wall and drop wall tended to flow through the expansion chamber in what might be regarded as three zones. Through the medial portion of the expansion chamber the gases tended to flow in an almost direct line from the throat to the combustion gas outlet, while a zone of relative stagnation existed at each side of the expansion chamber. The combustion gases which were thus more or less channeled straight through the medial zone of the expansion chamber naturally constituted the major portion of all of the 10 gases passing through the expansion chamber, and because of their direct flow at relatively high velocity the function of the expansion chamber was not adequately performed. Naturally, neither settling of dust and fly ash nor complete combustion of odor-causing vapors and 15 microscopic particles could occur if the major portion of the combustion gases were channeled at relatively high speed straight through the expansion chamber at the medial zone thereof.

Broadly, therefore, it is an object of this invention to 20 provide an incinerator having the general arrangement described in said copending application and from which there is virtually no emission of fly ash, dust, visible smoke or odor.

More specifically, it is an object of this invention to 25 provide means in an incinerator of the character described for effecting a substantially uniform flow of combustion gases across the width of the expansion chamber whereby all of the gases flowing therethrough are deflected toward the bottom of the expansion chamber and thus greatly decelerated, to thereby promote the necessary fly ash settling and secondary combustion by which smokeless and odorless incineration is achieved.

It has also been learned that to some extent the output 30 of smoke, dust and odor from an incinerator can be controlled by regulation of the volume and length of the throat conjointly defined by the partition wall and drop wall, that is, by providing an optimum spacing between the partition wall and drop wall and an optimum overlap between the bottom of the drop wall and the top of the 35 partition wall; and it is therefore another specific object of this invention to provide an incinerator wherein the optimum length of throat is preestablished and wherein the drop wall is mounted in such a manner as to greatly facilitate the empirical determination of optimum spacing between the drop wall and partition wall, which varies with load and local draft conditions.

Another specific object of the present invention is to 40 provide a simple and inexpensive drop wall for an incinerator of the character described which, by reason of its configuration, affords virtually smokeless and odorless combustion by effecting a distribution of gases flowing through the throat defined thereby such that the flow of gases through the expansion chamber is substantially uniform across the width thereof.

With the above and other objects in view which will appear as the description proceeds, this invention resides in the novel construction, combination and arrangement

of parts substantially as hereinafter described and more particularly defined by the appended claims, it being understood that such changes in the precise embodiment of the herein disclosed invention may be made as come within the scope of the claims.

The accompanying drawings illustrate several complete examples of the physical embodiments of the invention constructed according to the best modes so far devised for the practical application of the principles thereof, and in which:

Figure 1 is a longitudinal sectional view through an incinerator embodying the principles of this invention;

Figure 2 is a horizontal sectional view taken on the plane of the line 2—2 in Figure 1;

Figure 3 is a vertical cross-sectional view taken on the plane of the line 3—3 in Figure 1;

Figure 4 is a view similar to Figure 3 but showing a modified embodiment of the invention;

Figure 5 is a fragmentary longitudinal sectional view, taken on the same plane as Figure 1, showing how the drop wall is mounted for adjustment towards and from the partition wall;

Figure 6 is a view similar to Figure 5 but showing a modified embodiment of the invention; and

Figure 7 is a cross-sectional view through the upper rear portion of the incinerator, similar to Figures 3 and 4, but showing another modification of the invention.

Referring now more particularly to the accompanying drawings, in which like numerals designate like parts throughout the several views, the numeral 5 designates generally an incinerator comprising a front wall 6, rear wall 7, top wall 8 and side walls 9. The above identified copending application describes in detail the general arrangement of the incinerator, as well as the construction of the individual modules 10 of which these walls are preferably, but not necessarily, formed.

The interior of the incinerator is divided by a transverse partition wall 11 into a combustion chamber 12, in front of the partition wall, and an expansion chamber 13 behind the partition wall. In the upper rear portion of the incinerator, and preferably centered between the side walls, is a combustion gas outlet 14 which communicates the expansion chamber with a stack (not shown). With the modular construction described in the aforesaid copending application this outlet is conveniently located in the rear wall, near the top thereof, although obviously it could also be situated in the top wall, or even at the upper rear of one of the side walls as at 15 in Figure 7. In any event, practical considerations require the size of the outlet to be such that its major dimension in the direction crosswise of the incinerator, i. e., perpendicular to its side walls 9, is considerably less than the distance between the side walls. Accordingly, the outlet is localized to only a portion of the width of the expansion chamber, being centered with respect thereto in Figures 1 to 6 and entirely at one side thereof in Figure 7.

The bottom of the combustion chamber is defined by a grate 16 elevated above the base of the incinerator and onto which the rubbish and other material to be burned is deposited through a charging door 17 which forms the front portion of the top wall. A clean-out door 18 in the front wall permits access to an ashpit 19 below the grate as well as enabling combustion residue to be cleaned off of the grate itself.

The partition wall 11 extends from one side wall of the incinerator to the other, and its upper free edge is spaced below the top wall of the incinerator to permit combustion gas to flow thereover from the combustion chamber on its way to the expansion chamber. Just before it enters the expansion chamber, and immediately after crossing the upper edge of the partition wall, the combustion gas must flow through a narrow throat 20 wherein its rate of flow is abruptly accelerated. This throat is conjointly defined by the upper portion of the partition wall and the lower portion of a drop wall 21 which ex-

tends across the incinerator from one side wall to the other and depends from the top wall behind the partition wall. The depth of the drop wall is of course greater than the space between the top wall and the free upper edge of the partition wall, so that the free lower edge 22 of the drop wall is disposed below the upper edge of the partition wall. The length of depth of the throat, as defined by the distance the lower edge of the drop wall is spaced below the upper edge of the partition wall, is of major importance in achieving optimum performance. Contrary to what might be expected, it has been found that the length or depth of the throat must be kept fairly short, and for best results the throat length or "overlap" of partition wall and drop wall should be on the order of 2½ in. to 4 in., depending upon the size of the incinerator.

As the hot combustion gas flows at high velocity through the throat 20, secondary combustion air is inducted into it through a pair of air inlets 23, one in each side wall 20 of the incinerator, adjacent to the throat. The combustion gas flowing through the throat along with the inducted secondary combustion air, has a substantial velocity and downward impetus, but immediately after leaving the throat and entering the relatively large expansion chamber, the 25 gases are rapidly decelerated and thence make their way, at comparatively low velocity, upwardly to the outlet 14, with secondary combustion occurring as the gases thus proceed through the expansion chamber.

To insure adequate deceleration of the combustion 30 gases, the volume of the expansion chamber should be not less than 75% of that of the combustion chamber, and preferably is at least 90% thereof. Moreover, the desirable low velocity flow in the expansion chamber can 35 not be realized if the lower portion of the drop wall extends below the upper edge of the partition wall a distance greater than that indicated, nor can such flow conditions obtain if the spacing between the drop wall and partition wall is not correct. This spacing, it has been 40 found, should be from about one to three times the mean throat length or depth—i. e., one to three times the mean distance which the bottom edge of the drop wall is spaced 45 below the top edge of the partition wall, the exact spacing varying with the type of refuse to be burned in the incinerator and the combustion conditions which normally obtain therein as determined by the type of primary combustion fuel employed (gas, oil, etc.), stack height, and other factors which may vary from one installation to another.

In general, the area of the throat, as measured on a 50 horizontal plane intersecting the drop wall and the partition wall, should be about eight percent (8%) of the area of the grate.

To facilitate adjustment and enable the optimum spacing of the drop wall from the partition wall to be readily 55 determined by experimentation, the drop wall preferably comprises a monolithic block of refractory material or the like having downwardly facing shoulders 27 at the ends of its lower face which seat on lengthwise extending ledges 28 in the side walls of the incinerator. These ledges have substantial length to permit considerable forward and backward adjustment of the drop wall as indicated in dotted lines in Figure 5.

It will be understood that the thickness of the drop 60 wall is sufficient to enable it to remain upright on these ledges without additional support, and its own weight restrains it against displacement. After the correct location of the drop wall has been found by experiment, it may be readily secured in place with small amounts of mortar, as at 29, to prevent its accidental movement during 65 cleaning of the incinerator.

Maintenance of a uniform flow across the entire width of the expansion chamber is promoted by employing a slightly modified drop wall 21a with a lower edge configuration which tends to discourage combustion gases 70 from "channeling" straight through the central portion of

the expansion chamber, or taking the shortest route to the combustion gas outlet. To this end the depth of the drop wall 21a varies from point to point across the width of the incinerator, with that portion of the drop wall which is nearest the combustion gas outlet being deepest. More specifically, where the outlet 14 is centered between the side walls in the upper rear portion of the incinerator (which is the conventional arrangement and is depicted in Figures 1-6, inclusive), the lower edge 22a of the drop wall 21a is convex, as best seen in Figure 4, being curved on a wide radius to have its lowest portion 24 substantially midway between the side walls. However, where installation requirements necessitate an asymmetrical location of the combustion gas outlet, as for example at one side of the top wall (as illustrated at 15 in Figure 7), the bottom of the drop wall must also be asymmetrical.

In the case of the arrangement shown in Figure 7, the drop wall 21b is substantially quadrilateral, with its lower edge 22b slanting downwardly toward the side of the incinerator at which the outlet is located.

Where the combustion gas outlet is disposed substantially midway between the side walls, and the bottom edge of the drop wall is convex, the curvature of the lower edge of the drop wall need not be very great to obtain the desired results. It has been found adequate, on a drop wall for an incinerator which measures seventeen to eighteen inches between side walls, to have the center of the lower edge of the drop wall about 1 1/4 in. below the ends thereof.

In small incinerators, especially, it has been found desirable to use a drop wall having a substantially wedge shaped cross section, as for instance the drop wall 21c shown in Figure 6, wherein the front surface 26 slants forwardly downwardly at an angle of about 15° to the vertical. This disposition of the front face of the drop wall, together with a convex configuration of the lower edge 22a thereof, defines a throat 20a which is both longest (in the direction of combustion gas flow) and narrowest (as measured from partition wall to drop wall) at a point substantially in a direct front-to-back line with the outlet, thereby effecting a spreading or redistribution of combustion gases flowing therethrough which not only makes for desirable uniform flow across the entire width of the expansion chamber but is also highly effective in deflecting combustion gases downwardly into the expansion chamber instead of permitting them to flow directly to the combustion gas outlet.

Actual tests have shown that an incinerator equipped with a drop wall embodying the principles of this invention produces substantially less odor and visible smoke output than previous incinerators operating under comparable conditions, even when the latter were provided with water scrubbing devices or other elaborate and expensive adjuncts for smoke control. With the drop wall located in its optimum position, an incinerator embodying the principles of this invention has been found by actual test to produce such negligible quantities of fly ash, dust and odor that its emissions are normally undetectable by the senses except immediately adjacent to the mouth of the stack.

From the foregoing description, taken together with the accompanying drawings, it will be readily apparent that this invention provides an incinerator which produces little or no smoke, dust, fly ash or odor by reason of the provision therein of an inexpensive and simple improved drop wall cooperating with a partition wall to define a correctly proportioned throat which promotes substantially uniform flow of combustion gases across the expansion chamber, so that all portions of the gas flowing through the expansion chamber are decelerated sufficiently to promote adequate secondary combustion and settling of fly ash.

What I claim as my invention is:

1. An incinerator comprising spaced parallel upright

side walls connected by spaced upright front and rear walls defining an enclosure; a flat bottom wall joined to said side front and rear walls; a top wall joined to said side, front and rear walls, said top wall being uniformly spaced from the bottom wall upon any longitudinal plane parallel to the side walls and for the full length of the enclosure; an upright partition wall extending from side wall to side wall parallel to the front and back walls and spaced therefrom to divide the enclosure into a combustion chamber at the front and an expansion chamber at the rear thereof, the upper edge of the partition wall being spaced from the top wall; a grate in the lower portion of the combustion chamber; a charging door in the top wall above the grate through which refuse to be burned may be deposited in the combustion chamber; opposite horizontal ledges on the side walls extending lengthwise thereof behind the partition wall; a drop wall having the ends thereof seated upon said ledges so that the position thereof with respect to the partition wall is readily adjustable, said drop wall extending from side wall to side wall and having its top edge contiguous to the top wall and its bottom edge at an elevation below the top of the partition wall, the horizontal distance between the partition wall and the drop wall being substantially between one and three times the average distance the bottom edge of the drop wall is spaced below the top edge of the partition wall so that combustion gases and products of combustion passing from the combustion chamber into the expansion chamber are caused to flow downwardly along the rear of the partition wall to the bottom of the expansion chamber; and means at the upper portion of the expansion chamber defining a combustion gas outlet for the incinerator.

2. An incinerator having front, rear, side and top walls, a partition wall intermediate the front and rear walls and extending from one side wall to the other with its free top edge spaced below the top wall, dividing the incinerator into a combustion chamber in the front of the incinerator and an expansion chamber at the rear thereof, the expansion chamber having a combustion gas outlet in its upper portion, said incinerator being characterized by: the fact that the combustion gas outlet is of such size and is so located that its major dimension in the direction perpendicular to the side walls is considerably less than the distance between the side walls; by the provision of a drop wall spaced behind the partition wall and extending from one side wall to the other, said drop wall projecting downwardly from the top wall and having its free lower edge spaced below the free top edge of the partition wall, and being spaced rearwardly of the partition wall a distance between one and three times the average distance the free lower edge of the drop wall is spaced below the free top edge of the partition wall, so that the drop wall and the partition wall cooperate to define a narrow throat extending across the width of the incinerator through which combustion gases from the combustion chamber enter the expansion chamber; and further characterized by the fact that said free edges of the drop wall and the partition wall are non-parallel to one another along their lengths and have such configuration that the throat conjointly defined by the partition wall and the drop wall has its greatest depth in that portion thereof which is nearest the combustion gas outlet so as to prevent substantially direct flow of gases from the throat to the outlet and thereby effect a substantially uniform flow of gases across the full width of the expansion chamber.

3. The incinerator of claim 2 further characterized by the fact that the combustion gas outlet is substantially centered between the side walls so that its laterally opposite side edges are spaced a substantial distance from the adjacent side walls; and further characterized by the fact that the non-parallel relationship between the free

edges of the partition wall and drop wall results from one of said free edges being symmetrically convex.

4. The incinerator of claim 3 further characterized by the fact that it is the lower edge of the drop wall which is symmetrically convex.

5. The incinerator of claim 4 further characterized by the fact that the front surface of the drop wall slants forwardly and downwardly so that the throat is longest and narrowst midway between the side walls of the incinerator.

6. The incinerator of claim 2 further characterized by the provision of means mounting the drop wall for bodily adjustment thereof toward and from the partition wall

so that the size of the throat defined therebetween may be varied to suit local combustion conditions.
